UNITED STATES PATENT OFFICE.

HENRY D. JAMES, OF EDGEWOOD, PENNSYLVANIA, ASSIGNOR TO WESTINGHOUSE ELECTRIC & MANUFACTURING COMPANY, A CORPORATION OF PENNSYLVANIA.

MAGNETICALLY-OPERATED DEVICE.

Application filed November 7, 1927. Serial No. 231,533.

My invention relates generally to electro-magnetically operated devices suitable for alternating-current systems, and particularly to means for retarding the action of such devices.

The object of my invention is to provide for controlling the action of an electromagnetically operated device by a thermally-responsive latch.

10 Another object of my invention is to provide for utilizing an electric current for heating a thermally-responsive latch and for interrupting the heating process, without opening the heating circuit, when the latch is sprung.

15 A further object of my invention is to provide for utilizing thermally-responsive devices having a delayed action for controlling the operation of the accelerating switches of a motor-control system.

20 For a complete understanding of the invention and the operation of its parts, reference may be had to the following description which should be read in conjunction with the accompanying drawing, in which:

25 Figure 1 is a side elevational view of a magnetically operated device constructed in accordance with the invention.

30 Fig. 2 is a top plan view of a thermally responsive latch.

35 Fig. 3 is a diagrammatic view of a system of control for an induction motor, showing an electromagnetically operated device constructed in accordance with the invention and connected in the control system.

40 Referring now to Figs. 1 and 2, a core 11 of an electromagnetically operated device is constructed in a substantially U-shape. A lever 12 having a tail piece 13 is pivotally mounted on one of the legs of the core 11. The lever 12 extends in a substantially horizontal plane, and an armature 14 is pivotally mounted on its inner end. As shown, the armature 14 is disposed to engage both legs of the core 11.

45 A magnetizing coil 15 of the device is mounted on one leg of the core 11 and is disposed to be connected to a source of alternating current (not shown). Upon the connection of the coil 15 to a source of supply, the 50 core 11 becomes energized to attract the arma-

ture 14 which seats itself on both ends of the core 11.

A bimetallic latch 16 is so mounted on the bolts 17 that it is associated with the tail piece 13 of the lever 12. The details of this 55 thermally-responsive latch are disclosed in the copending application of Charles H. Hodgkins, Serial No. 52,267, assigned to Westinghouse Electric & Manufacturing Company, but an understanding of its structure may be had from Fig. 2 of my drawing.

Upon the connection of the terminals 18 and 19 to a source of supply, current will traverse the latch 16, passing through the sections 20. It will be noted that the sections 65 20 are of smaller cross sectional area than the other portions of the latch connected in the same circuit and, at the sections 20, hot spots will occur upon the flow of current. The effect of the hot spots will be to buckle 70 the latch, when sufficiently heated, and it will assume the position shown in dotted lines, thereby releasing the tail piece 13.

A coil 21 of relatively few turns is wound 75 on a projecting arm 22 provided on the core 11. The terminals of the coil 21 are connected to the terminals 18 and 19 of the latch 16. Therefore, the coil 21, when energized, provides a source of energy for heating the latch 16. In its open position, the armature 14 rests 80 in contact with the projecting arm 22 and, therefore, when the coil 15 is first excited, and, when the lever 12 is latched open, by the latch 16, the path of the flux which has been set up in the core 11 by the energization of the coil 85 15 must pass through the lever 12, the armature 14, the non-magnetic adjusting screw 23 and the projecting arm 22 of the core, thereby completing the magnetic circuit.

It will be seen that, before the closure of the 90 armature 14, the flux will follow the path outlined above, rather than traverse the air gap existing between the core 11 and the armature 14, which path is of considerably higher reluctance than the first. In this way, a transformer action is established between the coil 15 and the coil 21, while the armature remains open, a current is induced in the coil 21 and supplied to the latch 16. When the current, induced in the coil 21, has been flowing for a 95 100

length of time sufficient to heat the sections 20 of the latch 16 to the point at which the latch buckles, the tail piece 13 will be released by the latch 16, and the armature will be allowed to close or seat itself upon the ends of the core 11.

Upon the closure of the armature, the magnetic path of the lines of magnetic force or flux will be confined to the core 11 and armature 14, so that the flux path through the projecting arm 22 is interrupted and the transformer action between the coils 15 and 21 is no longer existent. Thus, after the armature has assumed its closed position, current is no longer flowing from the coil 21 to the latch 16 and, since there is no source of energy for heating the latch, the latch will cool and resume its original shape.

Referring now to Fig. 3, an application of the invention to a system of control for an induction motor 24 is shown. The operating coil 15 of the magnetically operated device is connected across one phase of the supply line 25 for the motor 24. When the main switches 26 are closed, the coil 15 becomes excited and the core energized. Since the lever 12 is held open by the latch 16, the path of the flux set up in the core 11 by the excitation of coil 15 will be through the lever 12, the armature 14 and the projecting arm 22, from whence it returns to the core 11.

When an alternating flux exists in the projection 22, a current will be induced in the coil 21, which will be conducted through the conductors 27 to the terminals 28 which are connected, one to the terminal 18 and the other to the terminal 19, of the latch 16. Then the current which is induced in the coil 21 flows through the latch 16, heating the sections 20 and, after a short period of time, causing the latch to buckle and release the tail piece 13, which will allow the closure of the armature 14.

Upon the closure of the armature 14, the projecting arm 22 will be eliminated from the magnetic circuit and no further transformer action between the coils 15 and 21 will occur. Thus, the inductive influence having been removed, no current will flow into the latch 16, and it may return to its normal position.

When the armature 14 is closed, it actuates a contact member 29 and short-circuits the starting resistor 30 for the motor 24. The time delay caused by the thermally-responsive latch 16 constitutes a very desirable feature for this type of control system, since it is quite necessary that there be an appreciable interval of time between the impression of the line voltage on the motor and short-circuiting of the starting resistor 30. The length of the aforesaid interval of time may be varied in accordance with the operating conditions of the motor by varying the cross sectional area of the sections 20 of latch 16, or by means of

the adjusting screw 23 which varies the air gap between the armature 14 and the core 11 and thereby decreases the current output of the coil 21.

Since my invention may be modified in various ways without departing from the spirit thereof, it is to be understood that the scope of its application is in no way limited to the embodiment hereinbefore set forth.

I claim as my invention:

1. In an electromagnetically operated device, a substantially U-shaped core disposed to provide a path for magnetic flux, a coil for energizing the core connected to an alternating-current source of power, an armature pivotally mounted for movement relative to the core, said armature being disposed to engage the core and form a closed magnetic path, a bimetallic latch disposed to retain the armature in its open position, an arm projecting from one side of the core, said arm being disposed to engage the free end of the armature when in its open position, a secondary coil wound on the projecting arm, said secondary coil being disposed to receive energy through induction from the first coil and to supply energy for heating the bimetallic latch, thereby springing said latch after a time interval and allowing the closure of the armature, and means for eliminating the secondary coil from the magnetic path.

2. The combination with an electromagnetically operated device for use in alternating-current circuits, of a secondary coil disposed to have current induced in it by the operating magnetic flux of the device when in its open position, means for eliminating said secondary coil from the magnetic path when the device is in its closed position, a thermally responsive latch for retaining the device in its open position, and means whereby said latch may be actuated by the current supplied from the secondary coil.

3. A time-element relay comprising, in combination, a main core member, an armature member disposed to engage the main core member to establish a main magnetic circuit, means for moving the armature relative to the core member, an auxiliary core member associated with the main core member, said auxiliary core member, main core member and armature moving means being disposed to establish a magnetic circuit, and a thermally responsive latch for the armature moving means cooperative to retain the armature spaced from the main core member, coils mounted on said main and auxiliary core members, said coils being inductively associated, the thermally responsive latch being connected to the coil on the auxiliary core member and responsive to current flowing in the coil on the main core member thereby to release the armature and interrupt the inductive action between the coils.

4. In a time-element relay, main and aux-

iliary coils inductively related, a movable armature for establishing a closed magnetic circuit through the main coil, to interrupt the inductive action between the coils, a thermal-⁵ ly responsive latch connected in circuit relation with the auxiliary coil, said latch being operative to maintain the movable armature in a predetermined position to establish an auxiliary magnetic circuit to cause an inductive action between the coils.

In testimony whereof, I have hereunto subscribed my name this 31st day of October, 1927.

HENRY D. JAMES.
